CONTAINER FOR FRAGILE COOKIES
OR THE LIKEGilbert C. Gettelman, Milwaukee, Wis., assignor
to Charles A. Wilkinson, Milwaukee, Wis.

Application May 19, 1951, Serial No. 227,156

3 Claims. (Cl. 206—72)

1

This invention relates to containers for fragile cookies or the like.

There is an increasing public demand for high quality cookies, particularly for those having a high butter content. Cookies of this type are extremely fragile, and it has not been possible to provide for boxed shipment thereof, because no container heretofore available was capable of preventing excessive breakage.

With the above in mind, it is a general object of the present invention to provide an improved container which is so constructed that breakage of even the most fragile cookies is prevented.

A further object of the invention is to provide an improved container of the class described wherein each cookie is individually hermetically sealed in a separate pocket of an elongated envelope, which envelope is formed of oil proof and moisture proof material to maintain the cookies in fresh condition indefinitely.

A further object of the invention is to provide an improved container of the class described wherein the cookies are suspended in a novel manner in the envelopes and out of contact with each other.

A further object of the invention is to provide an improved container of the class described having a novel frame in which the cookie containing envelopes are suspended, said frame being so constructed that the filled and sealed envelopes can be conveniently inserted therein prior to placement of the frame in the container.

A further object of the invention is to provide a container of the class described wherein the frame includes a pair of spaced, parallel end members formed with slits for snugly receiving the end portions of the envelopes, said envelopes being formed with offset portions at each end, which portions are disposed outwardly of the end members of the frame; whereby the ends of the envelopes are prevented from being pulled longitudinally inwardly through the slits of said frame members.

A further object of the invention is to provide an improved container of the class described wherein the spaced end members of the frame are each formed with a foldable reinforcing flange for preventing inward bowing of said frame members, said flanges also serving as handles for carrying the loaded frame during placement of said frame in the container, and said flanges being formed with cut-away portions communicating with the adjacent slits of the frame members to permit insertion or removal of the ends of the envelopes from said slits.

A further object of the invention is to provide an improved container of the class described wherein opposite walls of each envelope are sealed together along its upper edge, the sealed together area extending downwardly from said edge por-

2

tion and said edge being adapted to contact a cushion pad underlying the container cover to form a resilient shock absorber for the cookies in the envelope, the opposite edge of the envelope being spaced from the bottom of the container by the frame.

A further object of the invention is to provide an improved container of the class described wherein the cookie containing envelopes are made of transparent material, and wherein the frame acts to support said envelopes in an inclined position without permitting contact of adjacent envelopes as well as to attractively display the cookies when the container cover is removed.

10 With the above and other objects in view, the invention consists of the improved container for fragile cookies or the like, and all of its parts and combinations, as set forth in the claims, and all equivalents thereof.

15 In the drawings accompanying and forming a part of this specification, wherein is shown one complete embodiment of the preferred form of the invention, and wherein like characters of reference indicate the same parts in all of the 20 views:

Fig. 1 is a plan view of the frame removed from the container and in a position for loading, two filled envelopes being shown in position therein;

Fig. 2 is a front elevational view of the frame 30 shown in Fig. 1;

Fig. 3 is a side elevational view of the frame as indicated by the line 3—3 of Fig. 1;

Fig. 4 is a front elevational view of one of the 35 improved cookie containing envelopes alone, the cookies being shown in dotted lines;

Fig. 5 is a plan view of the improved container in loaded condition with the cover removed, a portion of the cushion pad being broken away; and

40 Fig. 6 is a transverse vertical sectional view of the loaded container taken along the line 6—6 of Fig. 5 showing the container cover in position.

Referring more particularly to Figs. 5 and 6 of the drawing, the numeral 10 indicates a rectangular container having a bottom wall 11, a 45 pair of opposite side walls 12 and 13, and a pair of opposite end walls 14 and 15. Positioned within the container 10 is a frame 16 which is shown most clearly in Figs. 1 to 3. The frame 50 16 includes a pair of spaced, parallel, elongated and preferably rectangular cardboard end members 17 and 18, each having a length substantially equal to the length of the inner surface of the end walls 14 and 15 of the container 10. The frame members 17 and 18 have a height substantially greater than the height of the side and end walls of the container 10 and are formed with a score line 19 extending longitudinally thereof at a height slightly less than the height 55 of said side and end walls. That portion of the

60

members 17 and 18 which is above the score line 19 is bendable to form a reinforcing flange 21. The frame members 17 and 18 are also formed with spaced, parallel slits 20 which are preferably inclined and which extend downwardly from the score line 19 to a point spaced from the bottom edge of said members.

The flanges 21 of the members 17 and 18 are also formed with cut-away portions 22 which communicate with the upper ends of the slits 20 for a purpose to be described hereinafter. Adjacent their ends the members 17 and 18 are each formed with a vertical slot 23 which extends downwardly from the score line 19 approximately half the distance to the lower edge, and which extends upwardly from the score line 19 a distance substantially equal to the length of the cut-away portions 22. Intermediate the length of the members 17 and 18, an inclined slot 24 extends downwardly from the score line 19 parallel with the slits 20, the slot 24 having an upward extension projecting into the flange 21 for a distance substantially equal to the height of the cut-outs 22. As shown in Fig. 3, each slot 24 extends downwardly approximately half the distance to the lower edge of the member in which it is formed.

Referring to Figs. 1 and 2, spaced, parallel, elongated rectangular frame members 25 and 26 each have a length substantially equal to the inside length of the side walls 12 and 13 of the container, and have a height slightly less than the height of the side and end walls. The members 25 and 26 are formed adjacent each end with a slot 27 which extends upwardly from the lower edge thereof approximately half the distance to the upper edge, thereby forming a tongue 28 outwardly of said slot.

The longitudinal frame members 25 and 26 are positioned with their end portions interlocked in the slots 23 of the frame members 17 and 18 as shown in Figs. 1 to 3, the tongues 28 extending through the slots 23, and the slots 27 receiving the portion of the members 17 and 18 below the slots 23. The members 25 and 26 are formed with a plurality of equally spaced slots 29 which extend downwardly from their upper edges approximately half the distance to the lower edge, as shown in Fig. 2.

Referring also to Fig. 6, a plurality of elongated, rectangular frame members 30 having a length equal to the length of the members 17 and 18 and having a height equal to the height of the members 25 and 26, are formed with end slots 31, similar to the slots 27 of the members 25 and 26, said slots forming tongues 32 outwardly thereof. The end portions of the transverse frame members 30 are interlocked with the longitudinal frame members 25 and 26 as shown in Figs. 1, 2 and 6, with the tongues 32 positioned outwardly of the members 25 and 26 and with the portion of the frame members 30 above the slots 31 being received in the slots 29 of the members 25 and 26.

The transverse frame members 30 are formed with a plurality of spaced, parallel, inclined slots 33 which are preferably aligned with and parallel to the slits 20 of the frame members 17 and 18. The slots 33 are preferably wider than the slits 20 but of substantially the same length, and the upper ends of the slots 33 may be outwardly flared as shown in Fig. 6. Each of the frame members 30 is also formed with a slot 34 which extends downwardly from the upper edge and

which is parallel to and aligned with the slots 24 in the members 17 and 18. An intermediate longitudinally extending frame member 35 has a length substantially equal to that of the frame members 25 and 26 and is slightly wider. The frame member 35 is formed with slots 36 adjacent its ends, said slots extending upwardly from the lower edge and being similar to the slots 27 of the frame members 25 and 26. The member 35 is formed with a plurality of intermediate slots 37 which are similar to the slots 36 and which are spaced apart a distance equal to the spacing between the frame members 30. The longitudinal frame member 35 has its ends interlocked with the frame members 17 and 18 in the inclined slots 24. The intermediate portions of the member 35 are interlocked with the transverse frame members 30 in the manner shown in Figs. 1 and 6, so that the portion of each of the frame members 30 which is below its slot 34 is received in a slot 37 of the frame 35. Similarly the portion of the frame member 35 which is above each of the slots 37 is received in a slot 34 of one of the transverse frame members 30.

Referring to Fig. 4, the numeral 38 indicates an elongated envelope which is preferably made of flexible, transparent moisture proof and oil proof thermoplastic sheet material. The envelope 38 may be made from a single extent of sheet material having a length substantially equal to the inner length of the side walls 12 and 13 of the container and having a width equal to approximately twice the length of the slits 20 and slots 33. This sheet is folded along its longitudinal centerline and is then heat-sealed at its ends in a manner to form offset retaining portions 39, as shown. The offsets 39 are made by forming indentations in the sealed-together end edge portions of the opposite walls of the envelope, adjacent indentations extending in opposite directions, as shown in Fig. 3. The envelope 38 also has its opposite walls heat-sealed to each other along a plurality of transverse lines 40 which are spaced apart in a manner corresponding to the spacing of the frame members 30, to form a plurality of cooky pockets therebetween. A cooky, indicated by the dotted lines in Figs. 1, 4 and 5, is inserted in each of the cooky pockets of the envelope 38, and the open longitudinal edge of the envelope 38 is then heat-sealed throughout its length for a substantial distance inwardly from said edge, as at 41. This hermetically seals each cooky in a separate pocket of the envelope 38.

In loading the improved container, the frame 16 is arranged as shown in Figs. 1 to 3 with the flanges 21 folded outwardly. Envelopes 38 which have been filled and sealed are then loaded into the frame by having their end portions inserted through the cut-away portions 32 of the flanges 21 with the offset portions 39 at the ends of the envelopes located outwardly of the frame members 17 and 18 and below the score lines 19. Those portions of the envelopes 38 which are located immediately inwardly of the offsets 39 are snugly received in the slits 20 of the frame members 17 and 18, and the heat-sealed intermediate portions 40 of the envelopes are received in the slots 33 of the intermediate transverse frame members 30, as is shown in Figs. 1 and 6. In Fig. 6 cookies 42 are positioned in those envelopes 38 which have been loaded into the frame 16.

When the frame 16 has been completely loaded with filled envelopes in the manner de-

scribed, it can be bodily picked up by grasping the flanges 21, and can then be readily placed in the container 10, as shown in Figs. 5 and 6. A rectangular cushion pad 43, which may be formed of cellulosic material, and which has a length and width slightly less than the internal length and width of the container 10, is then laid on top of the loaded frame within the container. The flanges 21 are then folded inwardly over the pad 43, as shown in Fig. 5, and a cover 44 is fitted onto the open top of the box, as shown in Fig. 6.

The slits 20 and slots 33 in which the envelopes 38 are positioned, are spaced apart a sufficient distance to prevent contact of adjacent cooky carrying envelopes. While the inclination of the slits 20 and slots 33 is preferably in the neighborhood of 30° from the vertical, the angularity may be anywhere within the range of zero to 45° from the vertical. The flanges 21 of the members 17 and 18 not only serve as handles by which the loaded frame can be carried, but more important, they serve as reinforcing bridging members, when folded to the position of Fig. 5, to prevent inward bowing of the end members 17 and 18.

It is apparent that the cookies are in a suspended condition so that any shocks to which the container may be subjected will be absorbed by the flexibility of the envelopes. The envelopes 38 are spaced from the bottom of the container 10 by the frame members 17, 18 and 30, and the heat-sealed upper marginal portion 41, with the cushion pad 43, forms an efficient shock absorber to prevent shocks acting through or against the cover 44 from being transmitted to the cookies.

Due to the fact that each cooky is hermetically sealed in its own pocket in the envelope 38, the cookies remain fresh indefinitely. The use of transparent sheet material in the envelopes 38 combined with the inclination of the envelopes as they are supported, provides an attractive display of the cookies when the cover 44 and the pad 33 are removed from the container.

Various changes and modifications may be made without departing from the spirit of the invention, and all of such changes are contemplated as may come within the scope of the claims.

What I claim is:

1. In combination a container having four upright walls and having an open top, a plurality of spaced supporting strips positioned edgewise in and extending between a pair of walls within said container, means for holding said strips in said position, the outermost strip on at least one side having a flange foldable on its upper edge and provided with a free edge, each strip having spaced slits extending downwardly from its upper edge, and there being extension slots in the flange of said outermost strip which communicate at one end with the slits in the strip, the other ends of said extension slots terminating short of the free edge of the flange, corresponding slits in the several strips being disposed in rows which extend transversely of the strips, a plurality of elongated envelopes with each envelope engaged in a row of slits, each envelope having an end retaining extension which is of less length than the extension slot in said flange whereby when said flange is folded over the top of the container it serves to retain the envelopes in position and whereby when it is folded outwardly the retaining exten-

70
75

sions of the envelopes may be removed through the extension slots of the flange.

2. In combination a container having four upright walls and having an open top, a plurality of spaced supporting strips positioned edgewise in and extending between a pair of walls within said container, means for holding said strips in said position, the two outermost strips each having a flange and said flanges having free edges which are foldable toward and away from one another, each strip having spaced slits extending downwardly from its upper edge, and there being extension slots in the flanges of said outermost strips which communicate at one end with the slits in said strips, the other ends of said extension slots terminating short of the free edges of the flanges, corresponding slits in the several strips being disposed in rows which extend transversely of the strips, a plurality of elongated envelopes with each envelope engaged in a row of slits, each envelope having end retaining extensions which are of less length than the extension slots in the flanges, whereby when said flanges are folded over the top of the container they serve to retain the envelopes in position and whereby when these flanges are folded outwardly the retaining extensions of the envelopes may be removed through the extension slots of the flanges.

3. In combination a container having four upright walls and having an open top, a plurality of spaced supporting strips positioned edgewise in and extending between a pair of walls within said container, means for holding said strips in said position, the two outermost strips each having a flange and said flanges having free edges which are foldable toward and away from one another, each strip having spaced slits extending downwardly from its upper edge, and there being extension slots in the flanges of said outermost strips which communicate at one end with the slits in said strips, the other ends of said extension slots terminating short of the free edges of the flanges, corresponding slits in the several strips being disposed in rows which extend transversely of the strips, a plurality of elongated envelopes with each envelope engaged in a row of slits, each envelope having end retaining extensions which are of less length than the extension slots in the flanges, whereby when said flanges are folded over the top of the container they serve to retain the envelopes in position and whereby when these flanges are folded outwardly the retaining extensions of the envelopes may be removed through the extension slots of the flanges, and a removable cover for the open top of the container positionable over said flanges when the latter are in envelope retaining position.
